J. B. M. MILES

POLISHING MOP

Filed April 6, 1925

INVENTOR

JOHN B. M. MILES
By *J. B. Miles*
Atty.

UNITED STATES PATENT OFFICE.

JOHN B. M. MILES, OF HAMILTON, ONTARIO, CANADA.

POLISHING MOP.

Application filed April 6, 1925. Serial No. 21,018.

To all whom it may concern:

Be it known that JOHN B. M. MILES, a subject of the King of Great Britain, residing at Hamilton, in the county of Wentworth and Province of Ontario, Canada, has invented certain new and useful Improvements in Polishing Mops, of which the following is a specification.

My invention relates to improvements in 10 mops used for polishing hard wood floors, linoleum, oil cloth and the like with wax, and also for oiling all kinds of floors.

It is customary to surface finished floors 15 such as hard wood floors, linoleums and oil cloth with wax, and at the present time liquid wax is usually used for this purpose. It is also customary to surface unfinished floors such as plank floors of soft wood or lower grade hard wood used in stores, factories and the like, with oil.

A common mop comprising an absorbent padded tread attached to a weighted base having brackets to which an operating handle is pivoted, has been used for either of the 25 aforementioned purposes, and it is to this type of mop this invention relates.

While thus finishing floors, the solution is usually transported in a can or other vessel 30 and from time to time is poured in bulk here and there over the surface of the floor, later to be spread over the floor by means of the mop. This is a dilatory and vexatious procedure principally for the reason that usually too much solution is poured out in one place and obviously the operator must frequently divide his attention between the 35 mop and the solution container.

The principal object of this invention is therefore to provide a manually operated 40 and controlled feeding device for polishing mops, whereby the solution may be conveniently and readily applied to the floor in the proportions as required and at the absorbent tread of the mop.

A second important object is to provide 45 a device of the class specified which will be simple, durable, efficient in its function and inexpensive to manufacture.

These, together with further objects, may 50 be attained by the construction, combination and arrangements of the parts as will be hereinafter more fully described, illustrated

in the accompanying drawing, and as 55 attained in the claims hereunto appended.

Referring to the drawing:

Figure 1 is a top view of a polishing mop 60 constructed in accordance with this invention;

Figure 2 is a side elevation projected from 65 Figure 1;

Figure 3 is an enlarged detailed elevational view of the valve mechanism and component parts thereof; and,

Figure 4 is an enlarged detailed cross-sectional elevational view of the tread and its 65 related parts.

Similar reference characters refer to corresponding parts throughout the several views.

The mop to which this invention relates 70 consists preferably of the usual absorbent padded polishing tread 10 secured to a suitable base 11 usually of wood. A well known type of elongated handle 12 is pivotally secured to brackets 13. Sometimes a weight 75 is attached to said base for the purpose of eliminating some of the manual pressure necessary to properly finish a floor, and this weight is indicated by the numeral 11'.

The solution container is preferably in the 80 form of a cylindrical tank 14 which may be permanently or detachably secured to the handle 12 as desired and is disposed in an underslung or depending position as shown. This tank is provided with a cone-shaped 85 feeder or funnel 15 having a valve 16 secured to the small end. The upper or filler end of the tank is provided with a suitable stopper 17 and is dished so that the contents will not overflow the rim if the tank becomes 90 too full when filling, the tank being erect at this time.

The valve 16 is provided with a nipple 18 to which is fitted a length of tubing 19, the opposite end of which communicates with 95 an open area 20 formed in the central portion of the tread 10. An ordinary and well known device known as a "drain cock" may be advantageously used as the aforesaid valve, and the tubing 19 is preferably 100 formed of flexible metallic tubing, as this resists the deteriorating effects of oil and wax upon other substances such as rubber hose, although the latter is adaptable for the

purpose if periodically replaced. The outlet end of this tubing is led through a duct 20' in the base of the mop, and the solution flows thence to the floor to be taken up and spread by the parts of the tread 10 surrounding the open area 20.

The valve 16 is controlled by a rod 21 extending upwardly along the handle 12 and slideable in a longitudinal groove there-in. The lower end of this rod is connected to the valve arm 22 by means of a connecting link 23, and the upper end of the rod is formed into a suitable finger grip 21'. Thus the flow of the solution is controlled, and a helically coiled contraction spring 24 is adapted to maintain the valve normally closed.

There has thus been produced a simple and useful device of the class described and for the purpose specified; and now having fully and completely disclosed and ascertained the nature of this invention and the manner in which it is to be performed, what I desire to secure by Letters Patent, is:—

1. In a polishing mop of the class described including a base, operating handle and absorbent polishing tread on the base, a tank supported by the handle, a valve communicating with the outlet end of the tank, flexible tubing leading from said valve to said tread, and means for controlling said valve.

2. In a polishing mop of the class described including a base, operating handle and absorbent polishing tread on the base, a tank supported by the handle, a valve communicating with the outlet end of the tank, flexible tubing leading from said valve

to said tread, means for controlling the valve, and means for maintaining the valve normally closed.

3. In a polishing mop of the class described, including a base and an operating handle on the base, a polishing tread having a substantially centrally disposed open area therethrough extending from top to bottom, a tank supported by the handle, a valve communicating with the outlet end of the tank, flexible tubing leading from said valve to the said open area in the tread, and means for controlling the valve.

4. In a polishing mop of the class described, a base, an operating handle on the base, a polishing tread on the base, a tank supported by said handle, a valve communicating with the outlet end of the tank, flexible tubing leading from the valve to an opening in the central portion of said tread, a reciprocally slideable rod extending along said handle and adapted to control said valve.

5. In a polishing mop of the class described, a base, an operating handle on the base, a polishing tread on the base, a tank supported by said handle, a valve communicating with the outlet end of the tank, flexible tubing leading from the valve to an opening in the central portion of said tread, a reciprocally slideable rod extending along said handle, a valve arm on said valve, a link connecting said rod with the valve arm, and means for maintaining the valve normally closed.

In testimony whereof I have affixed my signature.

JOHN B. MILES.
